[57] CLAIM

The ornamental design of a rim, as shown and described.

DESCRIPTION

FIG. 1 is a front elevational plan view of the rim according to one variant of the present invention;

FIG. 2 is a rear elevational plan view of the rim according to FIG. 1;

FIG. 3 is a side elevational view of the rim of FIGS. 1 and 2;

FIG. 4 is a cross sectional view of the rim of FIGS. 1-3;

FIG. 5 is a cross sectional view of a cap which is mounted on the front elevational view of the rim according to FIGS. 1-4;

FIG. 6 is a front elevational plan view of a rim according to a further variant of the present invention;

FIG. 7 is a rear elevational plan view of the rim according to FIG. 6;

FIG. 8 is a side elevational view of the rim of FIGS. 6-7;

FIG. 9 is a cross sectional view of a large part of the drum of the rim of FIGS. 6-8;

FIG. 10 is a cross sectional view of a small part of the drum of the rim according to FIGS. 6-8;

FIG. 11 is a front elevational plan view of a rim according to a further variant of the present invention;

FIG. 12 is a rear elevational plan view of the rim according to FIG. 11; and,

FIG. 13 is a side elevational view of the rim according to FIGS. 11 and 12.
